CHAIN DRIVE VELOCIPED

Viktor Schreckengost, Cleveland Heights, Ohio, assignor
to The Murray Ohio Manufacturing Co., Nashville,
Tenn., a corporation of Ohio

Filed Nov. 20, 1962, Ser. No. 72,553

Term of patent 14 years

(Cl. D34—15)

Fig. 1.

Fig. 2.

*Fig. 3.**Fig. 4.*FIGURE 1 is a front perspective view of a chain drive velocipede showing my new design;

FIGURE 2 is a rear elevational view thereof with the broken line representation of the seat portion being omitted for convenience of illustration;

FIGURE 3 is a side elevational view thereof; and

FIGURE 4 is a top plan view thereof with the broken line representation of the seat portion being omitted for convenience of illustration.

The dominant features of my design reside in the portion shown in full lines.

I claim:

The ornamental design for chain drive velocipede substantially as shown and described.
